PACKAGE-EJECTING MECHANISM FOR VENDING MACHINES

Application filed April 9, 1926. Serial No. 100,963.

The invention relates in general to a coin control manually actuated vending machine of the type intended for use in vending different articles of manufacture and the invention specifically relates to a removable and replaceable unit containing all of the mechanism for ejecting the package. The present disclosure constitutes a further development of the invention disclosed in the 10 applications of Landon C. Manning, being Serial No. 66,906, filed November 5, 1925, and Serial No. 71,599, filed November 27, 1925.

The primary object in this application as was the case in application No. 66,906 is to 15 provide a simplified form of coin controlled and manually actuated package ejecting mechanism and the present disclosure distinguishes from this co-pending application in that it features a reduction in the number 20 of necessary parts which go to make up the completed structure. Further, the present disclosure features the providing of a stand- 25 ardized unit adapted to be assembled with other similar units to form the completed vending machine; is designed to withstand rough usage; is designed so that the manual force actuating the control handle is trans- 30 mitted directly to the package ejecting element of the mechanism without passing through the controlling coin; the parts are 35 organized so that the ejecting element can return idly to its initial position without resistance from the remaining packages in the reservoir and the invention otherwise em- 40 bodies functionally the desirable attributes of the vending machine more fully discussed in the pending application No. 66,906 and therefore this disclosure is to be regarded more particularly as another and more sim- 45 plified embodiment of the inventions defined in the above identified copending applica- 50 tions.

Various other objects and advantages of the invention will be obvious from an inspection of the accompanying drawings and in part will be more fully set forth in the following particular description of one form of device embodying my invention, and the invention also consists in certain new and novel features of construction and combina-

tion of parts hereinafter set forth and claimed.

In the accompanying drawings, Fig. 1 is a view in front elevation of the portion of a vending machine containing one of the package ejecting mechanisms constituting a preferred embodiment of the present invention;

Fig. 2 is a view in front elevation of the replacement unit as disclosed when the portion of the mechanism enclosing casing shown in Fig. 1 is removed;

Fig. 3 is a view in rear elevation of the unit shown in Fig. 2;

Fig. 4 is a view in side elevation of the structure shown in Fig. 1 as viewed from the left side of Fig. 2, with parts of the casing broken away to show internal construction and with the parts in position just after the actuator has been moved slightly on its actuating stroke; and

Fig. 5 is a view similar to Fig. 4 with certain parts omitted and with the adjacent side plate removed to show the actuator in full lines in its normal inoperative position, and in dotted lines showing the same at the end of its actuating stroke.

In the drawings and referring specifically to Figs. 1 and 4, there is disclosed a mechanism containing casing 10 provided with an inset face plate 11 preferably in the form of a stamping with an arcuate rear side 12 corresponding to a closing element hereinafter described. The face plate is provided with an L-shaped slot 13 including an upper broad portion 14 designed when the device is in its inoperative position to provide access to a coin slot 15 carried by a swinging actuator 16 hereinafter described. The slot 13 also includes a long vertically extending portion 17 which provides a guideway for a handle 18 projecting therethrough from the actuator 16. The actuator is provided on its forward side with a curved flanged guard plate 19 concentrically disposed relative to the axis of swing of the actuator and conforming to the curved rear side 12 of the front plate. The guard plate contains coin slot 15 and is designed when moved by the handle 18 from its normal inoperative position to move along the curved

rear side 12 and remove the coin slot back of the lower part of the face plate and thus prevent access to the slot.

The unit includes package ejecting mechanism which is enclosed within a frame comprising a pair of parallel, spaced apart side plates 20 and 21 held in their spaced apart relation by means of three spacing bolts, 22, 23 and 24, of which the bolt 23 is at the lower portion of the frame and constitutes a means for loosely pivoting the lower end of a package ejecting arm hereinafter more fully described. The side plates as originally constructed are identically alike so that they may be standardized and made interchangeable with each other and with the side plates of the similar units in the complete vending machine. These plates are preferably formed of pressed metal each provided with a large embossment 26 and therebelow with a small horseshoe shaped embossment 26' both designed to give strength to the plates and thus permit the use of relatively thin sheet metal plates for this structure. When installed in position the embossment 26' in the plate 21 is slit and bent to form stop 66 hereinafter described. The plate 20 is disposed with the hollow side of its embossment 26 facing inward to receive an electric magnet 39 and other parts of the mechanism housed within the frame. Each of the plates is provided on its front edge with laterally turned hanging brackets 27 and 28 which are designed to be hung on pins 29 projecting from the casing 10. From this construction it is appreciated that the unit as a whole may be simply hung in its proper position in the casing and in this way the ready replacement of a damaged unit or a different size unit may be obtained.

Each of the plates is provided at its upper edge with a readily replaceable L-shaped bracket 30 conventionally secured by its depending flange 31 to the outside of the adjacent plate. The other flange 32 of the bracket is inturned in the instant case but may be outturned where a large size package is to be vended. In either case these flanges coact to provide the bottom of a reservoir 33 for containing the packages P to be vended as shown in Fig. 4. The package support provided by these inturned flanges 32 are slightly spaced apart as shown in Fig. 3 so as to permit the passage therethrough of the upper end of the ejector arm 25 and its associated parts.

Passed perpendicularly through the side plates 20 and 21 and below the reservoir 33 is a pivot pin 34 on which is pivotally suspended the actuator 16. This actuator comprises a vertically hanging thin metal plate 35 to one side of which and adjacent its upper edge the handle 18 is secured and to a forwardly projecting front edge of which the guard plate 19 is secured. To one side and adjacent the upper edge of the plate 35 are

secured a pair of coin guiding strips 36 and 37 coacting to provide therebetween an inwardly and downwardly inclined coin passageway 38 leading from the slot 15 at its outer end towards coin stops adjacent the lower inner corner of the plate 35. This coin passageway 38 has positioned on one side of its inner discharge end and contained within the adjacent embossment 26 a conventional form of horseshoe magnet 39 for attracting out of the path of the coin any spurious token as is usual in such constructions. The inner end of the strip 37 forms a curved ejector edge 37' advanced by the downward movement of the actuator for forcibly removing from the magnet 39 any article held thereby as shown in dotted lines in Fig. 5. Positioned below the inner discharge end of the passageway 38 and in position to receive the proper coin C (see Fig. 4) discharged therefrom is a connector 40 for coupling the actuator 16 with the ejector arm 25. This connector is in the form of a bell crank lever and includes a long horizontally extending arm 40' pivotally mounted adjacent one of its ends on a pin 41 projecting laterally from the plate 35. The upstanding arm of the connector adjacent the pivotal mounting is provided with a coin stopping pin 42 and the proper coin C is intended following the initial movement of the handle 8 to fit between the pin 42, the rounded lower edge 53', and a fixed stop 43 secured to the side of the plate 35. The upper edge of this relative fixed stop 43 constitutes a guide for assisting the coin as it is discharged from the passageway 38 to fall into position and engage the pin 42 and therethrough control the connector.

The plate 35 is provided with an arcuate slot 44 spaced from but concentric with the axis of rotation of the actuator about its pivotal mounting provided by the pin 34. The slot provides a support for a pin 45 extending transversely through and in turn providing a support for the ejector arm 25. It is understood that normally and even when the proper coin is inserted there is no positive connection between the ejector arm and the actuator for the coin is not heavy enough to swing the connector. Assuming that the coin has not yet been forced into position to lift the connector into operative position as hereinafter described, the movement of the actuator by downward pressure on the handle 18 will cause the actuator to move past the pin 45, the pin idly riding in the slot 44 and therefore without effect on the ejector arm as will be noted from an inspection of Fig. 5. The connector is provided at its free forward end with an upstanding arm or finger 46 which normally is disposed to rest on a support 47 formed at the lower edge of the plate 35 as shown in Fig. 5. When thus disposed the connector is in position so that the upper edge of the finger 46 when swung

will be clear of and pass beneath the pin 45. Assuming that the proper coin C which initially rests on top of the two point support provided by the pin 42 and stop 43 as shown in Fig. 5 has been forced against the pin 42 and stop 53' by the advancing stop 43 the connector will be swung and the hook end provided by the finger 46 will be swung from the dotted line position shown in Fig. 5 and elevated into the position shown in Fig. 4 thus coupling the actuator with the ejector arm 25 through its supporting pin 45.

The ejector arm 25 comprises a flat plate 48 with its edges turned at right angles to provide side flanges 48' the lower ends of each of which are bifurcated as shown at 49, Fig. 4, and loosely straddle the lowermost spacing bolt 23. This connector provides a floating pivotal connection with the lower end of the ejector arm but the arm is free not only to rock about the bolt 23 as a center but is also free to move longitudinally, that is vertically, for a limited distance. It is apparent that the ejector arm is not supported from the pin 23 about which it rocks but is supported by the engagement of the pin 45 in the slot 44.

Pivotedly mounted between the flanges 48 at their upper ends is a package engaging tripping finger 50 designed in its operative movement to engage the lowermost package LP in the reservoir 33 and move the same off the support provided by the flanges 32 of the brackets 30 as indicated in Fig. 5. The finger 50 has a relatively long, heavy, depending tail portion 51 which tends to maintain the part 50 intended to engage the package normally in upstanding position when clear of the packages but which will permit the finger to be turned anti-clockwise into position to slide under the packages in the reservoir in its return movement from left to right in Fig. 5 to its normal position after having ejected a package from the reservoir.

It is a feature of this disclosure that the ejecting finger 50 passes across the bottom of the reservoir in a line substantially parallel to the seat provided by the flanges 32 and that during the ejecting stroke the finger 50 is below the next adjacent package in the stack. This movement is attained by a definite designing of the slot 44 in such way that the rotary movement of the actuator about its pivotal connection 34 will cause a straight line movement of the finger 50 after it has engaged the lowermost package LP. It is apparent that if the ejector arm was mounted to swing about a fixed axis at the pin 34 which is centered below the support 32 the upper end would describe an elevating arc across the top of the support. However as the curve of the slot 44 is downward or in the reverse direction, the arm as a whole is lowered on the bolt 23 as the upper end with the finger 50 is advanced across the package

support. The configuration of the slot in its relation to the pivot 34 and the length of the support may be worked out experimentally or mathematically following conventional practices in designing cam constructions. There is therefore provided in effect a pin and slot form of camming means which will translate a rotary movement of the actuator about its fixed support into a straight, linear movement of the package engaging finger 50 in its movements in both directions across the package support.

With the advance of the coin C from its initial position filled between the stops therefore shown in Fig. 4 into its final operative position shown in dotted lines in Fig. 5 it is guided between guideway forming plates 52 and 53 attached to the side plate 20 by conventional fastening means 54. The plate 53 is provided with a stop edge 55 disposed in the path of and against which abuts the coin C when the actuator approaches the end of its movement as shown in Fig. 5 and this forces the coin downwardly and out of the medium. The pin 42 at the end of its travel engages the bolt 22 and this interengagement tips the connector 40 and swings the same clockwise from its position engaging the ejector arm and positively returns the connector into its initial lowered position engaging the stop 47.

The ejector arm is positively moved in its retreat to its initial position by the engagement of the end of the slot 44 with the advanced side of the pin 45 so that as the actuator is either lifted or returned by spring action to its initial position, the ejector arm is returned positively to its initial position.

For the purpose of returning the actuator mechanically into its initial position, there is provided a return spring, or preferably a pair of relatively long return springs 56 and 57 which are connected by means of an equalizing plate 58 to a pin 59 projecting from the lower corner of the plate 20. The opposite upper ends of the springs are similarly connected through plate 60 with a pin 61 projecting laterally from the actuator plate 35 in spaced relation to but relatively close to the pivotal pin 34. The pin 61 projects through a short arcuate slot 62 formed in the side plate 20 as particularly shown in Fig. 4.

The actuator is provided with a non-return locking device including teeth 63 formed at the lower edge of the plate 35 engaging with a gravity controlled pawl 64 pivotally mounted on the side plate 20. This construction prevents the premature return of the actuator until the stroke has been fully completed, the coin C discharged and the connector restored to its initially, unclutched position. A curved plate 65 secured to the upper portion of the actuator acts as a stop for engaging the lower end 51 of the package ejecting finger to move the same positively into

its upstanding position in case it become stuck or is thrown into a horizontal position by the inertia of the end 51 when the ejector arm is returned quickly. This plate 65 also constitutes part of a means for locking the mechanism when the reservoir is empty but this forms no part of the present disclosure. In order to provide means for limiting the return of the ejector arm, the embossment 26' on the adjacent plate 21 is cut about its horse-shoe shaped inner edge and the material therebetween forming the tongue 66 is bent at right angles and a stop screw 67 threaded through an aperture 68 pinched therein to provide an adjustable stop against which the ejector arm is held by the springs 56 and 57.

In operation and assuming that the parts are in the full line position shown in the several figures it is obvious that an illegal token may be attracted by the magnet 39 and held from falling into operative position. A token so held will be moved by the advancing edge 51' against the downwardly inclined advanced edge 53' of the plate 53 and dropped from the machine without affecting the connector.

It is also obvious that when there is inserted a coin of two small a dimension, as is shown at *b* in Fig. 5, it will fall idly past the stops provided by the members 42 and 43 and will pass through the machine and be returned to the operator as is known in such structures.

Should a coin of the requisite dimension as shown at *C* be inserted through the coin slot 38 it will first fall into the position slightly above the position shown in Fig. 4 and resting on the pin 42 and advanced edge of the stop 43 but without effect to lift the connector. On the initial movement of the actuator by downward manual pressure on the handle 18 the stop 43 will be moved clockwise into forceful engagement with the adjacent edge of the coin. The coin will thus be forced horizontally into engagement with the edge 53' which in turn rolls the coin clockwise and forces the coin down into engagement with the side of the pin 42 swinging the pin and with it the connector from its inoperative unclutched position shown in dotted lines in Fig. 5 into the position shown in Fig. 4. The coin will eventually come to rest on the three point support provided by the pins 41, 42 and stop 43 as shown in Fig. 4. The manual force acting on the actuator will be thus transmitted through the coin and elevate the finger 46 into position in rear of the pin 45 also shown in Fig. 4.

The continued downward movement of the handle 18 will cause the actuator to swing the ejecting arm 25 with its package engaging finger 50 movable linearly across the bottom of the reservoir and remove from the stack the lowermost package as is usual in ejecting mechanism of the type disclosed.

As the handle 18 is lowered the slot 15 is of course removed from possibility of insertion of another coin and the guard 19 prevents any access to the mechanism through the slot in the front of the casing. In moving from the position engaging the pin 42 to the end of the actuator stroke the coin remains in position holding the light weight actuator in its operative position until the ejector arm has completed its actuating stroke and movement of the actuator just before the end of its stroke discharges the coin into a suitable receptacle provided therefore and not herein shown. The final movement of the actuator causes bolt 22 to return connector to its initial position.

The actuator is returned to its normal inoperative position by lifting the handle 18 or by the spring action as hereinbefore described. The long spring which has been placed under tension and elongated by this movement of the actuator reacts on the actuator and returns the same to its initial position and at the same time the ejector arm is moved back into its initial position. If for any reason the tripping finger is not in its upstanding position, the engagement of the depending end 57 with the curved plate 65 will cause the finger to be restored to its normal upstanding position as shown in Figs. 4 and 5 and the device is ready to be again actuated on the insertion of the proper coin.

Having thus described my invention, I claim:

1. In a vending machine, the combination of a mechanism containing casing having an opening, a face plate fitted therein, having an L-shaped slot and provided on its rear side with a curved face, an actuator pivoted concentrically of the curved rear face, said actuator provided with a guard plate conforming in curvature to said rear face and in juxtaposition to the same, said guard plate provided with a coin slot normally accessible through one part of the slot and said actuator provided with a handle movable along another portion of the slot, and said guard plate acting to close the slot.

2. In a vending machine, the combination of a manually controlled, pivotally mounted actuator provided with an arcuate supporting means disposed concentric relative to the axis of movement of the actuator, a rocking ejector arm normally supported from said arcuate means but otherwise free of any direct actuating connection with the actuator, said actuator normally free to swing idly past the ejector arm, a coin actuated connector pivoted to the ejector, normally disconnected from the ejector arm and adapted to be moved by actuator acting through a proper coin to move the connector into an operative position positively connecting the actuator with the ejector arm whereby a subsequent movement of the actuator in one

direction will cause the actuator to pull the ejector arm on its package ejecting movement.

3. In a vending machine, the combination of a manually controlled, pivotally mounted actuator provided with an arcuate supporting means disposed concentric relative to the axis of movement of the actuator, a swinging ejector arm normally supported from said arcuate means but otherwise free of any direct actuating connection with the actuator, said actuator normally free to swing idly past the ejector arm, a coin actuated connector pivoted to the ejector, normally disconnected from the ejector arm and adapted to be moved due to the presence of a proper coin thereon by the actuator to move into an operative position positively connecting the actuator with the ejector arm whereby a subsequent movement of the actuator in one direction will cause the ejector arm to move on its package ejecting movement, and said arcuate supporting means constituting part of a camming means between the actuator and ejector arm for causing the portion of the ejector arm engaging the package to move substantially in a straight line as the ejector arm is swung by the pull of the engaging connector.

4. In a vending machine, the combination of a manually controlled, pivotally mounted actuator provided with an arcuate supporting means disposed concentric relative to the axis of movement of the actuator, a swinging ejector arm normally supported from said arcuate means but otherwise free of any direct actuating connection with the actuator, said actuator normally free to swing idly past the ejector arm, a coin actuated connector pivoted to the ejector, normally disconnected from the ejector arm and adapted to be moved due to the presence of a proper coin thereon by the actuator to move into an operative position positively connecting the actuator with the ejector arm whereby a subsequent movement of the actuator in one direction will cause the ejector arm to move on its package ejecting movement.

5. In a vending machine, the combination of a manually controlled and pivotally mounted actuator, package ejecting means, a connector pivoted to the actuator and adapted to be moved into position to couple the connector with the ejecting means, and a stop disposed in the path of movement of the connector when moved by the actuator, said connector and stop coacting as they come together to force the connector positively from its engagement with the ejecting means as the actuator approaches the end of its package ejecting stroke.

6. In a vending machine, the combination of an actuator, package ejecting means, a connector adapted to be moved into position to

couple the connector with the ejecting means, and a stop disposed in the path of movement of the connector when moved by the actuator, said connector and stop coacting to force the connector away from its engagement with the ejecting means and into its normal inoperative position as the actuator approaches the end of its package ejecting stroke.

7. In a vending machine, the combination of a manually controlled actuator provided with a coin slot, a swinging package ejector, a coin controlled connector in the form of a bell crank lever pivoted to the actuator and movable bodily therewith, one arm of the actuator disposed in the path of the coin passing along said chute, and the other arm of the connector provided with means for engaging the ejector to swing the same on its actuating stroke when the actuator is manipulated, and means on the actuator for supporting said other arm of the connector when free of a controlling coin.

8. In a vending machine, the combination of a manually controlled actuator provided with a coin slot, a swinging package ejector, a coin controlled connector in the form of a bell crank lever pivoted to the actuator and movable bodily therewith, a short arm of the bell crank lever and the actuator provided with coin receiving stops at the inner end of the slot, the free end of the connector provided with a hook end for engaging the ejector to swing the same on its actuating stroke when the actuator is manipulated, and means carried by the actuator for supporting the free end of the connector in an operative position when free of a controlling coin.

9. In a vending machine, the combination of a pivotally mounted actuator provided with means forming a long coin passageway and having a slot concentric with its pivotal axis, a package ejecting arm provided with a pin projecting into said slot, a coin controlling connector pivoted to the actuator normally disposed in an inoperative position and adapted to connect the actuator with the pin on the ejecting arm, said connector provided with a coin stopping pin disposed in the path of the coin moving along said passageway and said actuator provided with a relatively fixed coin stop, said stop and pin coacting to receive and stop the further free movement of the coin as it is discharged from the coin passageway and a coin so received acting as a connection between the pin on the connector and the actuator to swing the connector from its normal inoperative position into operative position on the initial movement of the actuator.

10. In a vending machine, the combination of a manually controlled actuator mounted for oscillation about a fixed axis, a package ejecting arm mounted for rocking movement about an axis below the actuator axis, a coin controlled connector pivoted to the actuator

and adapted to be engaged by an inserted coin, a stop disposed in the path of movement of the coin and said coin reacting against said stop to move the connector into position to positively couple the actuator with the ejecting arm whereby the subsequent movement of the actuator will swing the ejector arm on its actuating stroke independently of the presence of the coin and means for discharging the coin prior to the termination of said actuating stroke.

11. In a vending machine, the combination of a manually manipulated actuator mounted for reciprocatory movement in a vertical plane and provided with means defining a coin passageway, package ejecting means including an upstanding lever, a normally inoperative connector provided with a hook end for engaging said upstanding lever, means at the inner end of said passageway operable through an inserted coin and controlled by the initial downward movement of the actuator on its actuating stroke for moving the coin into engagement with the connector and acting therethrough to move connector into position to couple the actuator with the ejecting means whereby the further downward advance of the actuator will positively actuate the ejecting means.

12. In a vending machine, the combination of a manually manipulated actuator provided with means forming a coin passageway package ejecting means, a normally inoperative connector, means at the inner end of said passageway providing a three point support for the coin, means including one of said coin supports operable through an inserted coin and controlled by the initial movement of the actuator on its actuating stroke for moving the connector into position to couple the actuator with the ejecting means whereby the further advance of the actuator will positively actuate the ejecting means, said subsequent actuation of the ejecting means being direct between the actuator and ejecting means and independent of the presence of the coin, and means for discharging the coin from said coin supports prior to the termination of the actuator on its actuating stroke.

13. In a vending machine, the combination of a package ejecting arm having its lower end bifurcated, fixed pivoting means engaged by said bifurcated end, a pin projecting laterally from said arm, an actuator provided with a camming slot containing said pin and a connector pivoted to the actuator and adapted to be moved into hooked engagement with said pin.

14. In a vending machine, the combination of a package ejecting arm having its lower end bifurcated, fixed pivoting means engaged by said bifurcated end, a pin projecting laterally from said arm, an actuator provided with a camming slot containing said pin and a connector pivoted to the actuator

and adapted to be moved into hooked engagement with said pin, and tripping means in the path of movement of the connector for removing the connector from its engagement with said pin.

15. In a vending machine, the combination of a package ejecting arm having its lower end bifurcated, fixed pivoting means engaged by said bifurcated end, a pin projecting laterally from said arm, an actuator provided with a camming slot containing said pin and a connector pivoted to the actuator and adapted to be moved into hooked engagement with said pin, and tripping means in the path of movement of the connector for removing the connector from its engagement with said pin, and a stop for locating the connector when removed from its engagement with the pin in position clear of the pin.

Signed at New York, in the county of New York and State of New York, this 27th day of March, A. D. 1926.
